UNITED STATES PATENT OFFICE.

CHARLES A. JUENGST, OF CROTON FALLS, NEW YORK.

SIGNATURE-GATHERING MACHINE

1,029,528

Specification of Letters Patent.

Patented Apr. 16, 1912.

Application filed February 10, 1911. Serial No. 607,829.

To all whom it may concern:

Be it known that I, CHARLES A. JUENGST, a citizen of the United States, residing at Croton Falls, in the county of Westchester 5 and State of New York, have invented an Improvement in Signature-Gathering Machines, of which the following is a specification.

My invention relates to improvements in 10 machines for gathering or collating signatures or sheets previous to connecting the same together as a magazine or book.

Heretofore in this art devices have been employed which were automatically brought 15 into operation when any gripper failed to take a signature or sheet or took more than one, but such devices stopped the whole machine and made it necessary to start the entire machine again when the cause for the 20 irregularity had been overcome.

The object of my invention is to obviate this difficulty, waste of time and power, by the employment of devices in a signature gathering machine wherein when a gripper 25 fails to take a signature or sheet, or takes more than one, the signature conveyer or conveyer chain is stopped and the consequent feed of signatures or sheets arrested and the grippers opened. In this condition 30 the grippers with their supporting and actuating devices swing idly without performing any function and the remaining parts of the machine being unaffected by the stoppage of the signature conveyer or chain, 35 continue their movements.

My invention relates to and is an improvement upon the devices shown and described in Letters Patent #731,921 of June 16, 1903, granted to Reinhardt, and #875,384 40 of December 31, 1907, granted to Smith.

In the device of my invention I employ receptacles for the piles of signatures or sheets, means including suitable grippers for taking such signatures or sheets one at a 45 time from said receptacles and depositing them upon an endless conveyer traveling through a receptacle common to all the signatures or sheets, means in series for actuating the endless conveyer and the grippers 50 and means for arresting the movement of the conveyer and causing an open position of the grippers at once that the grippers or any one of them fail to take a signature or sheet, or take more than one of the same. 55 The special features of my invention com-

prise a crank arm from the shaft of the series of control levers, a connecting rod from the said crank arm to a crank arm upon a shaft below the conveyer and which shaft carries a latch-arm. A loose sprocket 60 and its chain are upon a driven shaft which actuates the conveyer and the gripper devices. A notched hub is also upon said shaft and secured thereto. A pawl pivoted to the loose sprocket and carrying a trip 65 is designed to be engaged by the latch-arm aforesaid in order to effect the operative separation of the sprocket and chain actuating the conveyer from the driven and driving shaft, all of which is hereinafter more 70 fully set forth.

In the drawings Figure 1 is a side elevation and section of the essential parts in the signature-gathering machine and in which are shown the features of my improvement. 75 Fig. 2 is a section and end elevation of the shaft, sprocket and other devices at the lower part of Fig. 1. Fig. 3 is an elevation and partial section similar to Fig. 1, but with the parts in the opposite position and, 80 in the position which they will assume when the grippers have been thrown open after failing to take a sheet or after taking more than one signature or sheet. Fig. 4 is an elevation and section similar to Fig. 2, with 85 the parts in their disengaged position, and Fig. 5 is a sectional plan showing the detector arms and the relation that they bear to the rocker arm and to its finger, the path of which is backward and forward in a vertical plane, as hereinafter more fully described. 90

A suitable frame or end frame is shown at *a*, the lower part of which forms a support for the shaft *b* which may be the power 95 shaft or may be driven by a power shaft not shown, through intermediate means.

c represents one of a series of signature holding boxes which as are usually made, is provided with a swinging flap member by 100 which a signature or sheet at a time is presented to the grippers.

d represents the signature-receiving trough which is common to all the signatures or sheets, and *d'* a signature or sheet conveyer 105 running through the center of the trough *d* and preferably in a recess especially provided therefor below the level of the signatures or sheets so as to be substantially out of contact therewith; the said conveyer be-

ing supported by a frame, and having a cover 110 and side walls, and a bottom.

ing provided as usual with raised fingers or members d^2 for moving the signatures or sheets along through the trough d .

There are several frames a in the machine 5 according to the length of the signature gathering machine, that is to say, one at each end and one or more intermediate frames, and in the upper part of these frames there is a shaft a^1 in suitable bearings 10 extending the length of the machine, and the devices connected with this shaft and in which are included suitable pairs of grippers are all alike, consequently a description of one series is sufficient.

15 A gripper arm e provided with a hub e^1 is mounted on the shaft a^1 and on the lower end of this gripper arm e is a gripper e^2 which is fixed, or in other words, rigid with the arm e . On the shaft b there is an eccentric 20 and an arm 3 formed with said eccentric, and connected pivotally to the upper end of the arm 3 is a crank 4 one end of which is secured to the shaft a^1 and with the rotation of the shaft b the eccentric 2, the 25 arm 3 and the crank 4 are actuated to oscillate the shaft a^1 and swing the gripper arm e , the gripper e^2 and the parts connected therewith and actuated thereby, from the position Fig. 1 to the rearward position Fig. 33 in the arc of a circle whose center is the center of the shaft a^1 . In the frames a there are also shafts 5 6 and 7 which run lengthwise of the machine and connected with which are series of devices hereinafter de- 35 scribed.

A bar f provided with hub ends is mounted between the shafts 5 6. Connected to the bar f is a bracket f^1 and connected to the hub of the bar f is a bracket f^2 and these brackets 40 are provided with adjustable stop pins f^3 f^4 . An indicator arm g is pivotally connected to the bar f by a pivot pin 8 and a detector arm h is a prolongation of the arm g extending downwardly below the same pivot. There is 45 another detector arm i connected by a pivot 9 to the bar f and the detector arms h and i bear a parallel relation to one another. In fact the detector arm h is provided with a plate 10 and guide pins thereon which come 50 at opposite sides of the detector arm i and establish the parallel relation of the arms h and i to one another. On the lower ends of the arms h and i there are nuts h^1 and i^1 and on the nuts fingers h^2 and i^2 . Figs. 1 and 55 show quite clearly the relation of these arms, nuts and fingers to one another. There is a screw pin 11 on the bar f and another screw pin on the right hand end of the arm g and a helical spring 12 is stretched between these 60 pins and it serves in function to assist in holding the parts in their relation to one another in the extremes of their movement as in Figs. 1 and 3.

k is a gripper arm with a gripper k^1 pivotally connected to the lower end of the

gripper arm e and the grippers e^2 and k^1 are adapted to come together as two fingers in taking a signature or sheet from the holding box c so as to deposit the same with the movement of the mechanism into the receiving trough d .

l l^1 are toggle-bars; the bar l at its upper end connected by a pivot 13 to the upper end of the gripper arm e and the bar l^1 at its lower end connected by a pivot pin 14 to the gripper arm k . The toggle-bar l is provided with a striking face 15 adapted to come against the end of the stop pin f^4 and it is also provided with a hook below this striking face, to which is connected one end of a helical spring 16; the lower end of the spring 16 being pivotally connected to the rear or right hand end of the gripper arm k so that this helical spring is respectively connected or hooked to the toggle-bar and 85 the gripper arm.

m represents a rocker arm pivotally connected at 17 to the gripper arm e , and o o^1 o^2 are parts of an adjusting bar, the respective ends of which are pivotally connected to the rocker arm m and the gripper arm k , that is to say, o and o^1 are the ends of this adjusting bar which are pivoted to said parts, and o^2 is the center member, the rotation of which draws the parts o and o^1 nearer together or forces them farther apart. A helical spring 18 is at its upper end pivotally connected to the rocker arm m and at its lower end to a pivot pin connecting the gripper arm k to the lower end of the gripper arm e so that the contractile tendency of the spring 18 and the adjusted position of the parts o o^1 o^2 maintain a definite relation under tension between the rocker arm m and the gripper k . From the right hand 100 free end of the rocker arm m extends a detector finger m^1 and this is shown in Fig. 5 in its relation to the detector bars h^1 and the fingers h^2 and i^2 carried thereby.

The control lever in its respective parts is 110 shown at r r^1 . The same with the hub thereof is mounted on the shaft 7 and a hub also upon the shaft 7 is provided with a crank arm r^2 . The free end r^1 of the control lever is provided with an adjustable stop pin r^3 and passing freely through the gripper arm e there is a sliding pin r^4 . Extending downward from the crank arm r^2 is a connecting rod 19; at its lower end it is 115 loosely secured by a pin 22 to a crank 21 which crank is connected to a shaft 20. Only a single crank-arm r^2 from the shaft 7 and a single connecting rod 19 is needed with a bank or plurality of gripper devices, all the other devices being duplicated for 120 each hopper. On this shaft 20 there is a latch arm 23 adapted when depressed to engage a trip 24 which is preferably formed integral with a pawl 25; the trip and pawl being connected by a pivot pin 26 to a 125 130

sprocket s and the sprocket s in turn loosely mounted on a shaft v between a collar s^1 pinned to the shaft v and a hub t also connected to the shaft v and the shaft v in turn provided with suitable bearings 27 and 28. This shaft v is provided with a bevel gear 29 and the shaft b with a meshing bevel gear 30 so that the power and the rotation of the shaft b is communicated by the bevel gears 29 and 30 to the shaft v .

10 The hub t is provided with a notch which in the normal and operative position of the parts is engaged by the pawl 25; the arrow in Fig. 2 representing the direction of rotation, consequently the rotation of the shaft v through this pawl 25 turns the sprocket s and moves along the conveyer chain d^1 with the same, thus progressing the signatures or sheets through the receiving trough d .

20 The adjusting parts o , o^1 and o^2 of the bars are employed to regulate the gripping position of the grippers e^2 and b^1 according to the thickness of the signature or the sheet to be removed from the signature holding box c , as in this art and in connection with the series of grippers employed, it may be necessary to adjust some of the grippers differently from others, as books or magazines often have sheets interposed between the signatures and each gripper is adjusted to take the signature or sheet from the pile of signatures or sheets in the box adjacent thereto.

25 In the operation of the device and referring particularly to Figs. 1 and 3, the grippers and the parts connected to and suspended from the shafts a^1 , 5 , 6 and 7 are shown in Fig. 1 in the position in which the signature or sheet is grasped, and in the position, Fig. 3, in which the sheet is delivered into the conveyer receptacle, and it will be noticed that as these parts swing back and forth from the position Fig. 1, that the striking face 15 of the toggle-bar b comes against the pin f^1 and the toggle b^1 is straightened; the loose pin e^3 being free when the stop r^3 is moved through the gripper arm e as the toggle-bars straighten. The straightening of the toggle-bars opens the grippers, applies increased tension to the spring 16 and swings the rocker arm m from the position Fig. 1 into the position Fig. 3, so that with the backward movement of the parts the detector finger m^1 is raised out of the path of the fingers h^2 , i^2 so that the same does not come in contact with said fingers.

30 As the arms and gripper devices go forward to engage another signature or sheet, the sliding pin e^3 comes against the stop r^3 and the pin is pushed through the gripper arm e acting against the toggle-bars b , b^1 and turning the same to the position Fig. 1 and so bringing the grippers together to take a signature or sheet; the grippers being

held together by the tension of the spring 16 and the operations described being repeated with every back and forth swinging movement. So long as the swinging parts perform their proper functions and raise the detector finger m^1 out of the path of either the finger h^2 or the finger i^2 , the indicator arm g and the detector arms h and i remain stationary in the position shown in Fig. 1; the swinging parts passing back and forth past the same, and the detector arm h remaining in an inactive condition resting against the stop pin f^3 with a bracket f^1 .

Should the grippers fail to take a signature or sheet, they will on the forward movement come together and this will immediately change the relation of the gripper arm k and rocker arm m with its detector finger m^1 , so that the detector finger will be dropped with reference to the position Fig. 1 and then when the parts swing backward this detector finger m^1 will be brought directly into the path of the finger h^2 and contacting therewith will move the detector arms h and i and swing the indicator arm g so that it will strike the upper end of the control lever r swinging the same with its lower end r^1 into the position shown in Fig. 3; simultaneously turning the crank arm r^2 , moving downward the connecting rod 19 and consequently swinging the latch arm 23 down into the path of the trip 24; the grippers in their backward movement being opened as hereinbefore described. This action will therefore as the sprocket s comes around, move the pawl 25 out of its notch in the hub t and the sprocket and chain being thus freed from operative relation with the shaft v , the movement will be arrested. In this connection it will be noticed that the stop pin r^3 will be moved out of the path of the sliding pin e^3 , consequently when the grippers come forward there will be no mechanism to close them and they will swing backward and forward in an inoperative condition.

35 The same operation is performed by the parts if more than one signature or sheet be taken by the gripper, as then the grippers will be forced open beyond their adjusted position for a single signature or sheet, and the relation of the gripper arm k and rocker arm m will be changed so that the detector finger m^1 will be elevated. In the elevated position it will strike upon the finger i^2 instead of passing between the fingers i^2 and h^2 as in the normal condition and it will then act upon the detector arm i directly and effect the movement of the detector arm h and with it the indicator arm g which then strikes and swings the control lever r^2 , crank arm r^2 and rod 19 operating the crank 21, arm 23 and the trip and pawl engaged thereby as hereinbefore described and thereby stop the sprocket s and its conveyer chain d^1 and re-

lease the same so that in either event the conveyer chain and the movement of the signatures or sheets is arrested.

Whether one or more than one gripper device fails to take a signature or sheet or takes more than one signature or sheet, such condition will at once be visually apparent by the position of the indicator arm *g* and control lever *r* at between the normal position Fig. 1 or the shifted position Fig. 3 so that the attendant examining the pile or piles at the place or places indicated, can make the correction if there are too many signatures or sheets, or supply the deficiency if there are not enough. At once the correction has been made, the lever *r* and arm *g*, in the position Fig. 3, are manually returned to the position Fig. 1, when the machine starts automatically to repeat its regular 20 motions.

I claim as my invention:

1. In a signature gathering machine and in combination, grippers for taking the signatures or sheets, a conveyer onto which the signatures or sheets are delivered, means for moving the conveyer, means for arresting the movement of the conveyer whenever an abnormal position of the grippers occurs, and means for preventing the grippers closing and becoming operative until after the conveyer is again in motion.

2. The combination in a signature gathering machine with a receptacle for signatures or sheets, grippers and gripper actuating devices for removing the signatures or sheets, a trough receiving the signatures or sheets from the grippers and a conveyer moving through the same, of devices controlled by the thickness of the material taken by the grippers, and other devices actuated by the aforesaid devices for disconnecting the conveyer, whereby the movement of the conveyer is arrested.

3. The combination in a signature gathering machine with receptacles for the signatures or sheets, grippers and gripper operating devices for removing the signatures or sheets, a trough receiving the signatures or sheets and an endless conveyer moving 45 through the trough of a shaft and means for rotating the same, a driving sprocket for the endless conveyer mounted loosely upon said shaft, means for connecting said sprocket with said shaft for turning the sprocket, devices actuated by the gripper operating devices whenever an abnormal position of the grippers occurs and which devices are thereby shifted from an inoperative to an operative position and means associated with the 50 endless conveyer coupling devices and into the path of movement of which a member of

the aforesaid devices comes for effecting the disconnection of the endless conveyer and stopping the same.

4. The combination in a signature gathering machine, of grippers, adapted to be set for engaging a single signature or sheet, gripper supporting and operating devices, devices operatively associated with the latter devices which remain inactive so long as the grippers take the single signature or sheet for which they are set and which latter devices are operative when the grippers fail when an abnormal position of the grippers occurs, a shaft and a control lever operated by the movement of the latter devices, a shaft, a latch arm connected with said shaft, a crank arm on said shaft and a connecting rod and crank arm extending to the shaft of the control lever, an endless conveyer, a loose sprocket around which the same extends and a shaft to which said sprocket is connected, a hub on the latter shaft and a pawl and trip device pivoted to the loose sprocket and engaging the hub for the progressive movement of the endless conveyer and which trip is so positioned as to be in the path of the pawl on the aforesaid shaft when the same is lowered from the normal position, whereby the trip pawl is disengaged and the sprocket with its endless conveyer is disconnected from the power shaft.

5. The combination in a signature gathering machine, of a control lever, a shaft on which the same is mounted, a crank arm connected to the control lever and a connecting rod extending from the crank arm, a crank connected to the opposite end of the connecting rod, a shaft on which this crank is mounted, a latch arm also connected to the said shaft, a power shaft, a sprocket loose on said shaft, an endless conveyer passing around said sprocket and operated by the power shaft, a pawl and trip device pivotally connected to said sprocket, a hub fixed upon said power shaft and provided with a notch for the pawl of the trip device, the trip device being in the path of the aforesaid latch arm so that when the latch arm is dropped by the movement of the control lever, the pawl and trip device are swung on the pivot thereof by engagement with the latch arm, the sprocket and conveyer chain being thus released so that their movement is arrested.

Signed by me this 31st day of January, 1911.
